CLAIM

The ornamental design for a jewelry setting, as shown and described.

DESCRIPTION

FIG. 1 is a top perspective view of the jewelry setting showing my new design, shown in a state of use;

FIG. 2 is a bottom perspective view of the jewelry setting of FIG. 1;

FIG. 3 is a top view of the jewelry setting of FIG. 1;

FIG. 4 is a side view of the jewelry setting of FIG. 1, the opposite side view being identical thereto;

FIG. 5 is an end view of the jewelry setting of FIG. 1, the opposite end view being identical thereto; and,

FIG. 6 is another top-down perspective view of the jewelry setting of FIG. 1, shown in a state of use.

The broken lines immediately adjacent to the shaded areas represent portions of the jewelry setting and form no part of the claimed design. The other broken lines in FIGS. 1 through 6 showing a finger ring and gemstones represent environmental subject matter only and form no part of the claimed design.
